UNITED STATES PATENT OFFICE

115,622

DESIGN FOR A PICTURE FRAME

John H. Jewett, Detroit, Mich.

Application November 17, 1938, Serial No. 81,173

Term of patent 3½ years

To all whom it may concern:

Be it known that I, John H. Jewett, a naturalized citizen of the United States, residing at Detroit, in the county of Wayne and State of Michigan, have invented a new, original, and ornamental Design for a Picture Frame, of which the following is a specification, reference being had to the accompanying drawing.

In the drawing:

I claim:

The ornamental design for a picture frame, as shown.

JOHN H. JEWETT.
